FREDERICK GORDON COBB, OF LANCASTER, SOUTH CAROLINA, ASSIGNOR TO VEEDER-
ROOT INCORPORATED, A CORPORATION OF CONNECTICUT

CONTROLLING AND INDICATING MECHANISM FOR LOOMS

Application filed December 12, 1929. Serial No. 413,603.

My invention relates to controlling and indicating mechanism for looms.

Difficulty has heretofore been experienced in weaving lengths of cloth of definite yardage. In an effort to obtain such lengths, the practice of measuring the warp yarn and marking it in the slasher with colored or so-called "cut marks" has been followed, but this method is unsatisfactory since with different filling and different numbers of picks per inch different lengths of cloth are produced from a given length of warp. Further, the weaver is required to watch each loom closely in order to shut it down when the cut mark comes up in the process of weaving. Thus, in many cases, and particularly where the weaver has a large number of looms to serve, the cut mark is passed. As a result, the weaver has to shut down the loom and roll back the cloth to find the mark. This results in serious loss, arising not only from the short pieces thus produced and the delay, but from the doubling and wrinkling of the cloth during the rolling back process, which frequently requires the rolled back cloth to be classed as seconds. Another method of determining the length of the cloth woven has been to have the operative responsible for removing the cloth measure the diameter of the roll, as by a stick or the like. This method is also inaccurate, as no two looms are alike in the density with which they roll the cloth, so that, as a result, on different looms the same diameter of roll will represent quite radically different yardage. This method is also further inaccurate since an error in measurement of only a sixteenth or an eighth of an inch, when the roll of cloth is twenty to forty inches in circumference, causes a variation of several yards of cloth. Further, the operative whose duty it is to remove the cloth and who ordinarily has several hundred looms under his care, has to cover all of the various looms and does not know without an actual inspection of each loom and measurement with his stick which loom is ready to have the cloth removed.

My invention has among its objects to provide an improved controlling and indicating mechanism for looms, which is adapted to re-

move the above difficulties and substantially to reduce production costs and which is, further, particularly adapted to use under modern conditions where many looms are cared for by each weaver and each operative whose duty it is to remove the cloth. A more specific object of my invention is to provide an improved mechanism adapted automatically to stop the loom upon the completion of any predetermined yardage for which the mechanism is set, and thereby not only insure production of rolls of predetermined length, but also minimize the losses incident to delay, creasing, remnants, etc. Further objects of my invention are to provide improved counting and indicating mechanism automatically counting the production in yards and indicating at all times the number of yards woven, and to provide improved mechanism associated therewith and controlling the loom whereby the latter is stopped whenever a predetermined yardage for which the mechanism has been set, is indicated by said counting and indicating mechanism. Still another object of my invention is to provide improved cooperating indicating mechanism adapted to attract the attention of an operative to the loom whenever the predetermined yardage is completed, and automatically moved to indicating position when the loom is stopped, and movable into inoperative position whenever, after the cloth has been removed, the mechanism is again started. Other objects of my invention are to provide an improved and simplified structure whereby the above objects are obtained and which, further, is capable of being produced economically and readily applied to a wide variety of looms in general use without change in the loom mechanism. These and still other objects and advantages of my improved construction will, however, hereinafter more fully appear.

In the accompanying drawings I have shown, for purposes of illustration, two embodiments which the same may assume in practice.

In these drawings,—

Figure 1 is a perspective view of a portion of a loom equipped with my improvement;

trolling mechanism and its associated elements on a loom frame, certain parts of the loom being omitted to facilitate illustration;

Fig. 3 is a side elevation of the structure shown in Fig. 2, the view being from inside the loom frame and certain parts also being broken away to facilitate illustration;

Fig. 4 is an enlarged detail view of the upper portion of my improved mechanism mounted on a loom frame, the view being from the side opposite that shown in Fig. 1;

Fig. 5 is an enlarged plan view of certain of the mechanism shown in Fig. 4, the cover of the counter being removed and some of the flag and stop mechanism also being omitted to facilitate illustration;

Fig. 6 is a detail end elevational view of the drive mechanism connected to the counter, the view being from the left at the top of Fig. 5, and

Fig. 7 is a perspective view of my improved controlling mechanism applied to a different type of loom, certain of the loom mechanism being removed to facilitate illustration.

In the illustrative construction shown in Figs. 1 to 6, it will be noted that I have shown a loom of a standard type including the usual frame 1, take-up roll 2, and Draper type stop motion 3, with my improved mechanism carried on the frame 1 and operatively connected between the take-up roll 2 and stop motion 3, as hereinafter more specifically described.

Considering my improved mechanism more particularly, it will be noted that it includes a counter or register 4, comprising transfer mechanism having usual operatively connected transfer members or number wheels, carried in a suitable casing 5 and herein attached to the upper cross member of the loom frame 1 in a readily visible position and driven from the usual gearing which drives the take-up roll 2, and includes the change gear which regulates the number of picks of filling. Herein, the roll 2 is driven by usual spur gears 6 and 7 of that gearing, of which the former is coaxial with the roll 2 while the meshing intermediate gear 7, driven by the change gear (not shown), is larger and located below the gear 6, and both are, as usual, journaled on the frame 1. As shown, the gear 7 herein also meshes with a laterally disposed, much smaller pinion 8 suitably supported and journaled inside the frame 1 in a suitable horizontal supplementary frame 9 fixed to the frame 1. This pinion 8 preferably also has integral with it a coaxial beveled pinion 10 which in turn meshes with a cooperating beveled pinion 11 on a horizontally extending shaft 12 perpendicular to the axis of the roll 2 and likewise journaled in the frame 9. This shaft, on the opposite end from the pinion 11, also carries a similar beveled pinion 13. This herein meshes with a cooperating, similar beveled

pinion 14 likewise journaled in the frame 9 but vertically disposed. This pinion 14 is connected through shafting including a universal joint 15 with an upwardly disposed drive shaft 16, which is in turn connected through a corresponding universal joint 17 with the lower end of a vertically disposed counter driving shaft 18 suitably journaled in the frame 19 of the counter 4. Herein, it will also be noted that this shaft 18 carries on its upper end and within the counter casting a worm 20 which in turn meshes with a gear 21, carried on the transverse counter shaft 22 and operating the counter mechanism 4. The latter mechanism being of usual construction, it will thus be evident that, the size of the take-up roll 2 being known, and the counter 4 being driven from the driving connections of that roll through the driving connections described, the counter 4 will indicate at a glance in terms of yards the yardage completed at any given time. Also, the relation between the roll 2 and its drive being constant, it will be evident that the yardage count will be accurate irrespective of the size of the pick gear used, and that no corresponding adjustment of the mechanism is necessary when the pick gear is changed.

Associated with this yardage counting mechanism is also improved setting mechanism adjustable as desired and operable after the completion of any predetermined yardage. Herein it will be noted that this mechanism includes a gear 25, likewise meshing with the worm 20 but carried on a shaft 26 disposed at right angles to the counter shaft 22 and journaled in a vertical portion 27 of the counter supporting frame 19. This shaft 26 herein extends to the opposite side of the frame 1 from the portion 27 through an elongated bearing 28 in the frame 19. It also carries on its opposite end a worm 29 which in turn meshes with a cooperating gear 30 suitably fixed to the upper end of a vertical shaft 31, as by a nut 32. This shaft 31 in turn is journaled in a suitable bearing 33 at right angles to the bearing 28 and carried on a supporting member 34 adjustably connected, as by bolts 35, to the vertical portion 27 of the counter frame. Herein, these bolts 35 extend through suitable sleeves 36 formed on the frame portion 27 and extend below the frame 1, while the portion 27 has lugs 37 suitably attached to the counter carrying side of the frame by suitable means, as for example bolts 38. Thus, it will be noted that depending upon the gear and worm combination 29, 30, the shaft 31 will be rotated slowly so as to make a complete revolution during the completion of any predetermined number of yards. Further, by releasing the bolts 35, the member 34 may be adjusted laterally in such manner as to enable gears 30 of different size to engage with the worm 130

29, while obviously further variation may be obtained by changing the worm.

Associated with the mechanism just described and operative in any setting of the latter, is improved trip actuating mechanism, which is in turn operative through mechanism controlled thereby and hereinafter described, to stop the loom after a predetermined yardage has been completed. Herein, it will be noted that the shaft 31 has pivotally mounted thereon near its lower end a horizontally swinging pawl 40. It, further, carries below this pawl a disc 41 suitably adjustably attached to the shaft, as by a setscrew 42, so that it rotates with the shaft. This disc in turn carries an upstanding pin 43 which is adapted, upon rotation of the disc, to engage the pawl 40 and cause it to swing about its axis on the shaft 31. Thus, it will be evident that with the parts suitably adjusted, after a predetermined yardage has been completed the disc 41, which is slowly rotated throughout the operation of the counter, will be rotated in such manner as to drive the pin 43 and the pawl 40 to complete a revolution upon the completion of the predetermined yardage determined by the gear and worm setting then in use. Obviously, the same result will also occur when different gear and worm sizes are used.

Associated with the trip actuating mechanism above described, is also improved stop members carrying mechanism tripped thereby upon the completion of any predetermined yardage. This mechanism herein includes a stationary, vertically disposed frame 45, herein suitably bolted to a transverse member 46, which in turn is bolted to the member 34. This frame 45 herein has reciprocably mounted therein a vertically disposed rod 47. It also has an intermediate laterally projecting latch member 48, a bottom lateral extension 49 spaced from the latch member, and a top lateral extension 50. As shown, the rod 47 also has a coiled spring 51 thereon acting between the extension 50 and an adjustable collar 52 carried on the rod above the member 48, while the rod also carries, nearer its lower end, a similar adjustable collar 53 engageable with the top of the extension 49. Herein, the rod 47 is bifurcated at one end and between its ends provided with a resilient vertical extension 54 which, like the rod 47, also moves in the extension 49, herein in a suitable perforation 55. Herein, this portion 54 is also provided near its upper end with a notch 56 and adapted to interengage, in the elevated position of the rods and when the spring 51 is compressed, with a cooperating ledge 57 on the portion 48, a knife edge connection preferably being provided for accuracy. It will also be noted that it is provided with a beveled upper end 58 adapted to pass up along the ledge while springing the portion 54 outward into notch engaging posi-

tion, and that this end 58 extends into the path of the pawl 40 when the notch 56 is hooked over the ledge 57. Thus, it will be evident that whenever the pin 43 causes the pawl 40 to complete a revolution, i. e. upon the completion of any predetermined yardage determined by the size of the gear and worm combination 29, 30, then in use, the pawl 40 will engage the end 58 of the member 54 and push it back in such manner as to make it release the ledge 57 on the member 48. As a result, the member 54 and member 47 will move bodily downward in the frame 45 under the action of gravity and aided by the spring 51, until the collar 53 on the member 47 engages the lateral projection 49 on that frame.

Associated with the members 47 and 54 above described, and movable therewith and herein carried, through means hereinafter described, at the lower end of a bottom portion 59 thereon, is improved means adapted to cooperate with the loom stop motion in interrupting the operation of the loom. Herein, these means assume the form of a member 60 adapted to move vertically with members 47 and 54. When used with a well known Draper stop motion, as illustrated herein, this member 60 moves between one of the combs 61 and the fan 62 in such manner as to stop the oscillation of the latter and the consequent movement of the wire stop 63 connected thereto, which, it will be understood, in turn controls the eccentric bushing and clutch lever common to such Draper stop motions but which are not shown herein. Thus, the member 54 acts, when in its own elevated position, to hold the member 60 in an elevated position above the fan 62. In this position, the stop motion will be free to operate normally whenever a thread breaks and one of the drop wires 61' carried on the thread falls between its comb and the fan. It will be evident, however, that whenever the pawl 40 so engages the upper end 58 of the member 54 as to cause the notch 56 to release the portion 48, the members 47, 54 and 59 will move quickly downward in such manner as to lower the member 60 and, through the resultant interruption of oscillation of the fan 62, and the consequent operation of the clutch, shut down the loom just as if a thread had broken.

While non-adjustable means may be used under certain conditions, I have also shown improved adjustable connections between the member 59 and the member 60 whereby, while retaining a simple and rugged character, the mechanism may be made adaptable to various conditions in various looms. More particularly, it will be noted that a suitable adjustable collar 64 is attached, as by a setscrew, to the lower end of the rod 59, and that this collar has pivoted thereto, as at 65 and on an axis at right angles to the rod, a similar setscrew held collar 66, which in turn carries a rod 67. This rod 67 in turn carries a collar

68, similar to the members 64 and 66, and is connected by a pivot 69 at right angles to the rod with another collar 70 which is attached to the upper end 71 of the member 60. Thus, 5 it will be observed that a wide range of adjustment is made possible between the portion 59 and the member 60 in such manner as to enable the latter member to be disposed at various elevations and various angles 10 adapting it to a wide range of adjustment in service.

Associated with the mechanism so far described is also improved indicating mechanism movable into indicating position whenever the part 60 is dropped and movable into inoperative position after the cloth has been removed and the mechanism re-set. This mechanism herein is carried on the frame 45 and moves into indicating position upon 15 downward movement of the member 47. More particularly, it will be noted that an indicator in the form of a so-called flag or disc 75, ordinarily painted brightly to attract 20 attention extends upward from a pivot 76 on an upward extension 77 on the upper end of the frame 45. Herein, a short curved lower end 78 is provided on this member 75 on the other side of the pivot from the flag. This portion 78 in turn extends into the path of 25 a lateral lug 79 preferably carried on a collar 80 adjustably fixed on the upper protruding end of the rod 47. Attention is also directed to the fact that the flag portion 78, when depressed by the lug 79, causes the flag 30 75 to swing over center, as shown in Fig. 4. Also, when the lug is raised, the flag is free to be swung back manually into its inoperative horizontal position. Thus, when the flag 75 is up, it will remain up even if the 35 rod 47 is raised. On the other hand, when the flag is down and the rod 47 is dropped down by the action of the pawl 40, the lug 79 will engage the portion 78 of the flag and elevate the latter into the indicating position 40 illustrated in Fig. 4. Accordingly, whenever a predetermined yardage has been completed, not only will the loom be stopped, but the indicator or flag 75 will be raised. Thus, the operative having charge of cloth removal 45 on the looms in a room will be able to tell at a glance over the room which looms are ready to have the cloth removed, while production is greatly increased by causing the looms which have made a predetermined length of 50 cloth to have attention at once and thus promptly be put back into operation. Attention is also directed to the fact that my register is so located in the drive of the tripping mechanism that it totals the output of 55 the loom, i. e. the yardage of the successive predetermined lengths, and does not require resetting. More particularly, it will be noted that no resetting whatever of the register is required, the same instead continuing to 60 count the yardage in the predetermined 65

lengths and automatically starting over whenever necessary.

As regards operation, it is believed that the operation of the several mechanisms will be clear from the foregoing description, and 70 that a detailed description of the operation is accordingly unnecessary. Instead, it is believed to be sufficient to say that, depending upon the gear and worm combination 30, 29 in use to predetermine the number of yards 75 desired, the loom will be stopped by the member 60 engaging its fan 62 whenever the predetermined yardage has been completed and the flag or indicator 75 simultaneously raised to call the attention of the operative to the 80 need for removing the cloth. Further, it will be evident that when the cloth has been removed, it will only be necessary to raise the member 59 and its associated rods 47 and 54, so that the notch 56 on the latter engages the 85 ledge 57 on the member 48, and press down the flag 75 by hand, in order to re-set the whole mechanism. It will of course also be evident that at any stage the yardage which has already been completed will be indicated 90 on the yardage counter 4, thereby giving the operators an additional indication of the progress of the loom toward completion of its predetermined yardage.

In Fig. 7 I have illustrated my improvement applied to a stop motion of the Crompton & Knowles type and including the usual slotted, relatively sliding members 81 and 82 peculiar to that type of stop motion. In this construction, it will be noted that the member 60 is adapted to be moved into the slots in these members when the same register, and that it thus functions substantially as heretofore.

As a result of my improvement, both the weaver operative and the operative whose duty it is to remove the cloth, are materially helped, particularly where, as under modern conditions, each of these men has to look after many looms, running, for example, in the case of the weaver, from 50 to 100, and in the case of the operative who removes the cloth, from four to eight hundred in number. The weaver by a glance at the counter can keep track of the yardage completed. Further, whenever a loom is stopped, if the flag is up, he knows, even from a distance, that it has woven its yardage, and accordingly does not need to go to it; whereas, when a loom is shut down and the flag is not raised, he knows that a broken thread or other difficulty makes it necessary to go to that loom. Also, it will be noted that in this construction the mechanism operates without change irrespective of the size of pick gear, thereby eliminating all delay incident to adjustment of the yardage counter after a change in pick gears. The weaver also is wholly freed from the necessity for watching for the cut marks on the warp yarn heretofore used to indicate 110 115 120 125 130

length, and consequently, can leave the looms to their own devices in that regard. As a result of these and other advantages obvious to those skilled in the art, it will be evident 5 that each weaver can attend to a substantially greater number of looms. As for the operative whose duty it is to remove the cloth, he can at a glance over the room ascertain which looms have their flags raised, and thus 10 concern himself only with those looms and go directly from one to another. Further, as compared with the previous stick method of determining yardage, the human element is eliminated and accuracy of yardage assured. 15 Attention is also directed to the fact that due to my improved construction, even should a weaver raise the rods and re-set the mechanism, the flag will stay up and thereby call the cloth remover's attention to the loom. 20 From the mill standpoint, also, not only is the mill enabled to fill quickly and efficiently orders for rolls of a given yardage, but the time loss required in rolling back rolls is 25 eliminated, and the creasing of the cloth incident thereto is also avoided, as is also the time required to cut off the excess yardage and the large losses incident to the sale of the short excess portions as shorts, remnants, etc., which must be sold at a discount. An 30 overseer coming into a room is also enabled at a glance to determine by the number of raised flags whether the cloth remover is keeping up with his work. Attention is further directed to the fact that the average 35 worker prefers the mechanism since no figuring is necessary, and he can keep better track of production in terms of yards than be can in terms of picks, as indicated in certain previous devices. Also, since pay is 40 based upon production, disputes which are frequent where pick measurements are used, are minimized by my improved mechanism. Other advantages will also be apparent to 45 those skilled in the art.

45 While I have herein specifically described two embodiments which my invention may assume in practice, and have particularly described the same as driven from the take-up 50 roll drive and acting upon the stop motion of the loom ordinarily operative to stop the loom when a thread is broken, it will be understood that these embodiments are described for illustrative purposes and that in 55 certain embodiments the invention may be modified and cooperate with other elements and also include specifically different mechanism, all without departing from its spirit, and that I intend to include all such modifications within the scope of the appended 60 claims.

What I claim as new and desire to secure by Letters Patent is:

65 1. The combination with a loom, of a register continuously driven thereby during weaving and totalizing the production of suc-

cessive lengths as woven, and means independent of the register for effecting interruption of loom operation after each predetermined length has been woven and registered 70 on said register.

2. The combination with a loom, of a register continuously driven thereby during weaving and totalizing the production of successive lengths as woven, and means driven by the register drive and adjustable in 75 any position of the register for effecting interruption of loom operation after each predetermined length has been woven and registered on said register.

3. In combination with a loom, a register continuously driven thereby during weaving and totalizing the production of successive lengths as woven, and means adjustable to vary the length without resetting any part of said register for effecting automatic interruption of loom operation after each predetermined length has been woven and registered 85 on said register.

4. In combination with a loom, a register continuously driven thereby during weaving and totalizing the production of successive lengths as woven, and means operative in any position of said register for effecting interruption of loom operation after a predetermined length has been woven and registered 90 on said register.

5. In combination with a loom, a register continuously driven thereby during weaving and totalizing the production of successive lengths as woven, and means resettable in any position of said register for effecting interruption of loom operation after a predetermined length has been woven and registered 100 on said register.

6. In combination with a loom, a register continuously driven thereby during weaving and registering the production in linear units as woven, and manually resettable mechanism for interrupting loom operations after predetermined linear totals have been woven having means adjustable independently of said register to vary the selected cloth lengths. 105

7. In combination with a loom, a register continuously driven thereby during weaving and registering the production in linear units as woven, and automatically operable and manually resettable mechanism for interrupting loom operation after predetermined linear totals have been woven and both operable 115 and resettable in any position of said register mechanism.

8. In combination with a loom, a cloth output register operatively connected thereto, and automatically operative manually resettable 125 and adjustable means for interrupting the operation of said loom after the completion of various predetermined lengths of cloth, said register being operatively connected to total 130 said lengths and said means being adapted to

- be adjusted and manually reset independently of said register.
9. In combination with a loom, a register successively totalizing the production of successive lengths during successive loom operations, means for interrupting loom operation after a predetermined length has been woven and registered on said register, means for adjusting said means independently of said register, and means for enabling manual resetting of said interrupting means independently of said register.
10. In combination with a loom, a register continuously driven thereby during weaving and totalizing the production of successive lengths as woven, manually resettable means for effecting automatic interruption of loom operation after a predetermined length has been woven and registered on said register and indicating means moved into indicating position by said interrupting means and movable into non-indicating position after resetting.
11. In combination with a loom, a register continuously driven thereby during weaving and totalizing the production of successive lengths as woven, tripping means adjustable independently of the register to vary the lengths, and automatically operable loom controlling means tripped off by said means independently of said register.
12. In combination with a loom, a register continuously driven thereby during weaving and totalizing the production as woven in successive lengths, tripping means operative in timed relation to the register and adjustable independently of the register to vary the lengths, and loom controlling mechanism automatically movable into weaving interrupting position when tripped off by said means and having means for manually resetting the same independently of said register and tripping means.
13. In a loom having a part movable during weaving and means for stopping the loom, a register geared to said part, a trip actuating member geared to said register, and means for actuating said stopping means resettable manually independently of said register and having a trip released by said actuating member and an automatically operative member automatically operative when said trip is released and controlling said means for stopping the loom.
14. In combination with a loom having a take-up roll and a stop motion, register mechanism continuously registering the loom production and operatively connected to said roll, and mechanism likewise operatively connected to said roll but independent of the register mechanism for interrupting operation of said stop motion after a predetermined production.
15. In combination with a loom having a take-up roll and a stop motion, register mechanism continuously registering the loom production and having its drive operatively connected to said roll, and mechanism driven by the register drive but independent of the register mechanism for interrupting operation of said stop motion after a predetermined production.
16. In combination with a loom having a take-up roll and a stop motion, register mechanism continuously registering the loom production and having its drive operatively connected to said roll, and mechanism driven by the register drive and having change gears independent of said register mechanism and register drive, for interrupting operation of said stop motion after weaving predetermined lengths.
17. In combination with a loom having a take-up roll and a stop motion, a register comprising a series of operatively connected transfer members and a driving shaft therefor, mechanism for automatically interrupting operation of said stop motion after weaving a predetermined length and likewise having a driving shaft, and a common driving member operatively connected to said roll and to both of said shafts.
18. In combination with a loom having a take-up roll and a stop motion, a register comprising a series of operatively connected transfer members and a driving shaft therefor operatively connected to said roll, tripping mechanism driven by said shaft, and manually resettable mechanism tripped off thereby after a predetermined production and controlling said stop motion.
19. In combination with a loom having a take-up roll and a stop motion, controlling mechanism for said stop motion having a member movable to interrupt the stop motion, mechanism normally holding said member in elevated inoperative position, and releasing mechanism for said last mentioned mechanism operatively connected to said roll.
20. In combination with a loom having a take-up roll and a stop motion, a register operatively connected to said roll and having a driving member, co-operating controlling means for said stop motion having mechanism driven by said driving member and independent of said register and a stop motion engaging member controlled by said last mentioned mechanism, and indicator mechanism movable into indicating position when said stop motion engaging member moves into engaging position.
21. In a loom having a take-up roll and a stop motion, a register geared to said take-up roll, a trip actuating member geared to said register, and stop motion controlling mechanism tripped off by said actuating member after a predetermined movement thereof and having a member controlling said stop motion and means for automatically resetting

- 5 said mechanism upon reverse manual movement of the latter.
- 6 22. In combination with a loom having a take-up roll and a stop motion, register mechanism having operatively connected transfer members and a drive therefor operatively connected to said roll, change gears driven by the register drive but independent of the same and of said transfer members, tripping mechanism driven by said gears, and mechanism tripped by said actuating mechanism and having a stop motion controlling member.
- 10 23. In a loom having a take-up roll and a stop motion, a register geared to said take-up roll, a trip actuating member geared to said register, reciprocable manually resettable mechanism automatically tripped off by said actuating member and having a stop motion controlling member, an indicator flag, means for automatically setting the flag in indicating position when the stop motion is interrupted, and means requiring independent manual movement of said flag into non-indicating position after said reciprocable mechanism is manually reset.
- 15 24. In combination with a loom having a take-up roll and a stop motion, a shaft operatively connected to said roll, tripping mechanism driven by said shaft and having change gears and a swinging actuating member actuated after a predetermined rotation of said gears, and manually resettable reciprocable mechanism automatically movable in one direction into a position controlling said stop motion when tripped off by said swinging member and reversely reciprocable manually to reset the same and release said stop motion.
- 20 25. In combination, a driving shaft, tripping mechanism driven by said shaft and having a movable actuating member actuated by said shaft after a predetermined rotation thereof, and a movable mechanism tripped off by said actuating member and automatically movable in one direction when so tripped off and reversely movable manually to reset the same.
- 25 26. In combination, a driving shaft, a tripping member movable about the axis of said shaft independently of the latter, means movable with said shaft and engageable with said tripping member to pick up the latter after each tripping operation and return it to tripping position, a co-operating member tripped off by said tripping member, and loom controlling mechanism operative by said tripped off member.
- 30 27. In combination, a driving shaft, a co-operating shaft, change gear means between said shafts, a swinging member on said second mentioned shaft, means rotatable with the latter shaft actuating said swinging member after a predetermined shaft rotation, and loom controlling mechanism tripped off by said swinging member.
- 35 28. In combination, a driving shaft, a co-operating shaft, change gear means between said shaft, a swinging member on said second mentioned shaft, means rotatable with the latter shaft actuating said swinging member after a predetermined shaft rotation, a reciprocable member released by said swinging member, a loom controlling member movable with said reciprocable member, and indicator mechanism actuated by said reciprocable member.
- 40 29. In combination, a driving shaft, tripping mechanism driven by said driving shaft and adapted to be operated after a predetermined length has been woven, reciprocable mechanism manually resettable and having means for automatically moving the same in one direction upon release and latch means holding the same during weaving and releasable by said tripping mechanism after a predetermined length has been woven, and loom controlling means movable by said reciprocable mechanism.
- 45 30. In combination, a driving shaft, tripping mechanism driven by said driving shaft and adapted to be operated after a predetermined length has been woven, reciprocable mechanism manually resettable and having means for automatically moving the same in one direction upon release and latch means holding the same during weaving and releasable by said tripping mechanism after a predetermined length has been woven, and a plurality of members carried by said reciprocable mechanism and adjustably connected thereto and to one another.
- 50 31. In combination, a driving shaft, tripping mechanism driven by said driving shaft and adapted to be operated after a predetermined length has been woven, reciprocable mechanism manually resettable and having means for automatically moving the same in one direction upon release and latch means holding the same during weaving and releasable by said tripping mechanism after a predetermined length has been woven, loom controlling means movable by said reciprocable mechanism, and indicating means controlled by said reciprocable mechanism and disposed thereby in different positions during weaving and when weaving is interrupted.
- 55 32. In combination, a register mechanism having operatively connected transfer means and a driving shaft therefor, tripping mechanism driven by said driving shaft, reciprocable controlling mechanism automatically reciprocable upon release having latch means holding the same during weaving and releasable by said tripping mechanism upon a predetermined rotation of said shaft, and loom controlling mechanism connected to said reciprocable mechanism.
- 60 33. In combination, a register mechanism having operatively connected transfer means and a driving shaft therefor, tripping mech-

anism driven by said driving shaft, reciprocable controlling mechanism automatically reciprocable upon release and having latch means releasable by said tripping mechanism 5 after a predetermined rotation of said shaft, loom controlling mechanism connected to said reciprocable mechanism, and indicating mechanism likewise operative by the latter.

34. A controlling and indicating attachment 10 for looms comprising a frame connectable to the loom, a register carried by said frame and comprising operatively connected transfer mechanism and a driving shaft therefor, operative connections for connecting said 15 register to a moving part of the loom, a controlling member automatically reciprocable in said frame upon release and having latch means for holding the same in an elevated inoperative position therein, loom controlling 20 and indicating members operable by said reciprocable member, and tripping means for said latch means carried on said frame and driven by said driving shaft.

35. The combination with a loom having a 25 take-up roll, a stop motion disposed longitudinally thereof beneath the cloth, and a frame having a portion above the cloth, register mechanism on said frame portion and operatively connected to said roll at one side of the cloth, of stop motion controlling mechanism carried by said frame portion and driven by said register drive but operable and adjustable independently of said register and having an automatically releasable and manually reset stop motion controlling member 30 co-operating with the stop motion, and an indicator member operable with said stop motion controlling member.

36. The combination with a loom having a 35 take-up roll, a stop motion extending longitudinally thereof beneath the cloth, and a frame carrying the same and having a portion above the cloth, register mechanism on said frame portion and operatively connected to said roll at one side of the cloth, of stop motion controlling mechanism carried by said frame portion and driven by said register drive but operable and adjustable independently of said register and having an automatically releasable and manually reset stop motion controlling member co-operating with the stop motion at one side of the cloth, and an indicator member operable with said stop motion controlling member, said register mechanism comprising transfer mechanism and having flexible driving connections between the same and said take-up roll, and 40 said stop motion controlling mechanism comprising a frame carried by said frame portion, a manually and automatically reciprocable member movable therein and having flexible connections thereon between the same and 45 the operating end of said stop motion control-

ling member, and a controlling mechanism for said reciprocable member driven through the register drive but adjustable at will independently of the register.

In testimony whereof I affix my signature. 70
FREDERICK GORDON COBB.
